FILAMENT MOUNTING FOR GAS-DETECTING APPARATUS

Application filed August 13, 1928. Serial No. 299,406.

This invention relates to detectors for combustible or inflammable gases of the type in which a heated filament is brought into contact with the atmosphere to be tested. If any combustible or inflammable gas be present the gas will be oxidized by contact with the heated filament and the temperature of said filament will be further raised. The increase in temperature depends upon the proportion 10 of combustible or inflammable gas present and the temperature of the filament may be measured by any suitable means and in any suitable manner. However, we prefer to measure this by noting the change in electrical resistance of said filament. While we prefer to employ a chemically pure platinum filament and to pass a sufficient electric current through it to maintain it at a temperature above 1,000° C. so that the oxidation proceeds 20 without catalytic action, the present invention is not limited to the use of any particular filament material or to a temperature of above 1,000° C.

It is obvious that if the heated filament be 25 brought into contact with an atmosphere containing inflammable gas or gases, an explosion might be caused. For this reason we surround the filament with one or more gauze jackets of the type used in the well known 30 miner's flame safety lamp. This gauze or set of gauzes serves to prevent any possibility of propagation of a flame from inside to the atmosphere outside the jackets. An object of our invention is to provide a mounting for 35 the filament such that the filament-heating current cannot flow unless the protective gauze jackets are in place. Another object of our invention is to provide such a mounting that the gauze jackets cannot be removed 40 in a shorter time than that required for the filament to cool down from the maximum temperature below that at which the inflammable constituent of the surrounding atmosphere could be ignited.

45 These and other objects of our invention will be evident from the following description of one embodiment of our device having reference to the accompanying drawings in which:

50 Fig. 1 is a vertical section through a device

constructed in accordance with one embodiment of our invention.

Fig. 2 is a vertical section through the filament holding unit thereof.

Fig. 3 is a horizontal section of said device taken on line III—III of Fig. 1.

Fig. 4 is a side view of the device, parts being broken away, and

Fig. 5 is a perspective view of one of the 60 gauze jackets.

In the drawings we show a mounting member 10 which is secured to a handle 11 in any suitable manner. The handle is provided with suitable means which are in fixed relation to the direction of the filament and which 65 convey to the operator a visual and tactile indication as to the direction of the filament.

A block 13, preferably made of insulating material, is mounted in the member 10 and held against rotation. This block is provided 70 with a center aperture 14 having a shoulder 15 near the bottom thereof. A shell 16 of conducting material engages the aperture below the shoulder. A helical spring 17 rests on the shoulder between the shell and the 75 upper part of the aperture. The block is also provided with one or more side openings 18. We prefer to employ two such openings diametrically opposed to each other. The upper part of the opening is provided with a 80 constricted portion or neck 19. On the under surface of the block are mounted four conductors 21, 22, 23 and 24. Conductors 21 and 24 are each connected to one conductor of a twin conductor cable 25 which connects 85 the detector mounting with any suitable device for measuring the change in electrical resistance of the filament and to a battery or other source of current for heating the filament. A portion of conductor 22 is in vertical 90 alignment with but spaced from a portion of conductor 21 and a portion of conductor 23 is similarly in vertical alignment with but spaced from a portion of conductor 24. The portions of the conductors which are in vertical alignment are preferably also in alignment with the side openings 18. Each of 95 these conductors are preferably provided with contact pieces 26 at the points in which they are in alignment. Conductor 22 is electrically 100

connected with the spring 17, and conductor 23 is provided with a contact piece for engagement with a filament-holding unit to be described below.

5 The filament-holding unit comprises a cup-shaped member 27 of a size to slide readily within the shell 16. The cup-shaped member is provided with pins 28 which fit in slots in the shell 16 and engage the spring 17. The 10 cup-shaped member is provided with an opening 31 in the bottom thereof and washers 32 and 33 of insulating material above and below said opening. The filament-holding unit is provided with two standards 34 and 35 for 15 supporting the filament. One of the standards 34 is secured to and in electrical contact with the cup-shaped member 27. The standard 35 extends through the opening 31 and the washers 32 and 33, the standard being smaller 20 than the opening 31 and held centrally in said opening by washers 32 and 33 whereby it is insulated from the cup-shaped member. The standard 35 does not touch the cup-shaped member and the space around the standard 35 25 is filled with a plastic non-combustible insulating material 36. A spacing member 37 of insulating material is provided for keeping the standards properly spaced. The upper portions of the standards are provided with 30 a bearing surface 38 with which a clamping member 39 engages. The ends of a filament 41 are held between the upper surface of the standard and the clamping member 39, the clamping member being held against the 35 upper portion of the standard in any suitable manner, as by screws 42. The ends of the standards may be held in fixed relation by spacing bars 43 which are secured to the ends of the standard in any suitable manner. 40 However, we have found that a position above and on each side of the filament is preferable. In order to support the spacers 43 the upper ends of the standards 34 and 35 are provided with upwardly and sidewardly extending 45 arms 44 upon which the spacers 43 are mounted. The spacers are made of insulating material or insulated from the standards. The clamping member 39 fits between the arms 44.

In order to prevent propagation of flame to 50 the surrounding atmosphere, from the gas burning at the incandescent filament, we provide one or more jackets of fine gauze such as are employed in the miner's flame safety lamp. While we have shown three, such 55 jackets we do not limit ourselves to any particular number as we may employ more or less than three. The inner jacket, regardless of the number of jackets used, may be constructed in accordance with the following description.

60 The inner jacket comprises a jacket proper 45 and a flanged base 46 which is secured to it in any suitable manner. The center of the base is provided with a recess to receive a 65 collar 47 carried by the filament holding unit.

This collar can engage the recess in the base 46 in only one position or in two positions 180° apart. The collar 47 has rotatably mounted thereon a pair of screws 48 for securing the filament-holding unit to the inner 70 jacket. The collar 47 fits the recess in the base of the jacket so closely that to remove the filament-holding unit the screws must be alternately and equally turned back a small fraction of their total travel. The total time 75 consumed in this, together with the other disassembling operations, is sufficient for the temperature of the filament to drop from the maximum possible operating temperature to a temperature below the igniting point of 80 the combustible components of the atmosphere. In this manner we have made it impossible for the unprotected filament while hot to come in contact with the gas-containing atmosphere. The inner jacket base also 85 carries a pair of projections 49 which are permanently secured thereto by any suitable means. These projections are adapted to register with and extend into the constricted portion 19 of the side openings 18 where they 90 engage plungers 52 which are held therein by the contacts on the lower portion of the insulating block. To insure complete electrical insulation these plungers are made of insulating material but may carry one or more wear-resisting members 53, of conducting material. Surrounding the inner jacket 45 we superimpose one or more additional jackets as 54, 54' provided with bases 55, 55' adapted to rest upon the adjacent lower base. A locking 95 ring 56 engages the outer portion of the mounting member 10 and is provided with an inwardly extending flange at the top thereof for engagement with the topmost base 55'. When all the jackets are in place, and the locking ring is screwed down to the end of its travel, the inner jacket base 46 is forced 100 downwardly, forcing the plungers down and closing the contact between conductors 21 and 22 and between conductors 23 and 24. At the same time the filament-holding unit is carried 105 downwardly by the inner jacket and contact is made between the lower end of standard 35 and conductor 23, and between the pins 28 and the spring 17. The current may now 110 flow from the cable through conductors 21 and 22, spring 17, pins 28, cup-shaped member 27, standard 34, filament 41, standard 35, conductors 23 and 24 and thence back to the cable. When the locking ring is unscrewed 115 the circuit is broken in one or more of these four places and the current is cut off from the filament. Moreover, due to the arrangement of the device as set forth above, it is impossible to remove the filament from the inner 120 jacket before its temperature has been so reduced as to make it impossible for the surrounding gas to be ignited. The mounting member 10 is provided with a shoulder 125 against which the locking ring fits when 130

screwed home. This is so positioned with relation to the upper flange of the locking ring that the circuit will not be closed unless the predetermined number of protective jackets are inserted around the filament.

We may provide a bonnet 57 around the gauze jackets, this bonnet being mounted upon the locking ring and provided with suitable apertures, for permitting the atmosphere being tested to penetrate to the filament. This bonnet serves to protect the gauze jackets from injury and also to prevent strong current of air from coming in contact with the filament. We may if we so desire provide a carrying hook 58 on the bonnet.

We have provided that the filament 41 is always in fixed relation to the handle. The filament holding unit is fixed relative to the base of the inner jacket by the engagement between the screws 48 and the base 46. The base in turn is in fixed relation to the insulating block by engagement between projections 49 and the side apertures 18. The insulating block is fixed to the mounting member 10 which is fixed on the handle.

We claim:

1. A head for gas detectors comprising a base, a protective jacket adapted to be secured to said base and a filament holding unit engaging said jacket and means holding said filament holding unit and jacket in engagement, said holding means being so situated that they can be operated only when the jacket is separated from the base.

2. A head for gas detectors comprising a block, pairs of spaced resilient conductors on said block, a filament-holding unit, a gauze jacket adapted to surround the filament, said jacket being provided with a base adapted to engage the filament holding unit, projections extending downwardly from the base of the jacket, actuating members movably supported by the block in a position to be engaged by the projections on the base of the jacket to force the spaced conductors together, and means for holding said jacket against said block.

3. A head for gas detectors of the type in which an electrically heated filament is exposed to the atmosphere to be tested comprising a block, a gauze jacket having its base in engagement with said block, means for supporting a filament within said jacket, conductors including a switch mounted on said block and in electrical circuit with said filament, a projection on the base of said jacket and switch actuating means adapted to be engaged by said projections.

4. A device as set forth in claim 3 in which the block is provided with a vertical hole into the upper part of which the projection of the jacket base is adapted to project; and in which the switch actuating member is a

plunger movably mounted in the lower part of said hole.

5. In a gas detector head, in combination, a gauze jacket, a base for said jacket provided with a recess, a filament holding unit, means on said unit fitting into said recess and opposed screws carried by said unit for securing said unit to the base of said jacket.

6. In a gas detector head, in combination, a gauze jacket, a base for said jacket provided with an opening, a filament-holding unit engaging said opening whereby the filament is disposed within the jacket and means for so securing said filament-holding unit to the base that the filament cannot be removed from the jacket in less time than is required for the filament to cool from the operating temperature to a temperature that will not ignite combustible gases.

7. A head for gas detectors comprising a casing, a block within said casing, a gauze jacket having a base for engaging said block, a projection on said base, a plunger movably mounted within said block in a position to be engaged by said projection, a pair of normally spaced conductors opposite said plunger, and means engaging said casing for forcing the base of said jacket against said block.

8. A gas detector head comprising a block having a central aperture and a side aperture, a plunger mounted in the lower part of said aperture, a conductor extending below both said apertures, another conductor extending below said side aperture and spaced from said first named conductor, means for supporting a filament holding unit in said central aperture, and means fixed relatively to said filament holding unit for projecting into said side aperture for engagement with said plunger.

9. A head for gas detectors comprising a block of insulating material having a central aperture and a pair of side apertures, a helical spring in the central aperture, a pair of spaced conductors disposed opposite each of the side apertures, one of the conductors being in circuit with said helical spring, one of the conductors of the other pair having one end disposed below said central aperture, a filament-holding unit disposed in said central aperture and provided with contacts adapted to engage the helical spring and the end of the conductor below the central aperture, means in said side apertures for forcing the spaced conductors of a pair together, a gauze jacket surrounding said filament, and projections carried by said jacket for engaging the contact closing means.

10. In a head for gas detecting devices of the type in which a heated filament is exposed to the atmosphere to be tested, a base having a recess extending downwardly from the upper surface, means for supporting a filament above said base, a jacket surrounding said filament for preventing propagation

of flame from said filament to the surrounding outside atmosphere, said jacket being provided with a projection adapted to fit into the recess in the base, conductors for supplying current to heat said filament, said conductors including a switch in normally open position, and switch actuating means disposed in the bottom of said recess for closing said switch.

11. A head for gas detectors comprising, in combination, a base member, means for supporting a filament above said base member, a plurality of gauze jackets surrounding said filament, said jackets being provided with bases engaging the bases of adjacent jackets, one of said bases engaging said base member, means for engaging another of said bases for holding all said bases in position on said base member, a conductor, including a switch disposed below the upper surface of the base member, for supplying current to said filament and a projection carried by the base of one of said jackets for operating said switch.

12. Means for mounting a filament comprising a pair of spaced standards, means for gripping a filament on each standard, a pair of arms extending obliquely from each standard and spacing elements connecting the arms of opposite standards.

13. A device as set forth in claim 12 in which the filament gripping means are at the end of the standards and the arms extend from the standard adjacent the gripping means.

14. A device as set forth in claim 12 in which the gripping means comprise the flat upper ends of the standard and a clamping member cooperating therewith.

15. A filament holding unit for a gas detecting apparatus comprising a shell, a standard electrically connected to said shell, a standard within and extending through said shell, means for insulating said second standard from said shell, means intermediate the ends of the standards for holding the standards in spaced relation, means for mounting a filament between the upper ends of the standards, arms extending obliquely from the upper ends of the standards and spacing members extending between said arms.

16. A filament holding unit for a gas detecting apparatus comprising a shell, a standard electrically connected to said shell, a standard within and extending through said shell, means for insulating said second standard from said shell, means intermediate the ends of the standards for holding the standards in spaced relation and means for mounting a filament between the upper ends of the standards.

17. A filament holding unit for a gas detecting apparatus comprising a shell, a standard electrically connected to said shell, a standard within and extending through said shell, means for insulating said second stand-

ard from said shell, means intermediate the ends of the standards for holding the standards in spaced relation, arms extending obliquely from the upper ends of the standards and spacing members extending between 70 said arms.

18. In a gas detector, a filament, conductors arranged to connect said filament with a source of electrical energy for heating the filament, a switch in at least one of said conductors, a jacket surrounding said filament and preventing unobstructed access of the atmosphere thereto, locking means requiring manipulation to permit the removal of said jacket from about said filament, and means 75 for preventing access to said locking means while said switch is closed.

In testimony whereof, we affix our signatures.

WILLIAM F. HUNT.
